(57) **CLAIM**

The ornamental design for a shield, as shown and described.

DESCRIPTION

FIG. 1 is a top view of a translucent shield showing my new design;

FIG. 2 is a front view thereof;

FIG. 3 is a back view thereof;

FIG. 4 is a right side view thereof;

FIG. 5 is a bottom view thereof;

FIG. 6 is a left side view thereof; and,

FIG. 7 is a side view of the shield showing the shield supported at one end of a flexible, adjustable support means. The broken line showing is for illustrative purposes only and forms no part of the claimed design.
